J. M. Moore

Attorney

UNITED STATES PATENT OFFICE.

HARRY W. HARGIS, OF CHARLOTTE, NORTH CAROLINA.

SMOOTHING PLANE.

Application filed May 31, 1923. Serial No. 642,501.

To all whom it may concern:

Be it known that I, HARRY W. HARGIS, a resident of Charlotte, in the county of Mecklenberg and State of North Carolina, a citizen of the United States, have invented certain new and useful Improvements in Smoothing Planes, of which the following is a specification.

My invention relates to improvements in smoothing planes and the main object being the provision of means capable of application to planes at the time of manufacture or upon planes in general use, which will prevent clogging or choking of the material in the throat or passage of the plane.

Another object of my invention is the provision of means of the character and for the purpose stated which will add such a small amount to the cost of the plane as to make my improvements highly desirable and satisfactory.

Another object of my invention is the provision of means which may be applied to planes in use or at the time of manufacture, which will be simple, strong and durable in construction and greatly enhance the efficiency and practicability of the plane.

With these objects in view, my invention consists of means of the character and for the purpose stated embodying novel details of construction, combination and arrangement of parts, substantially as described and defined by the claims, and as shown in the accompanying drawing, in which:

Figure 1 represents a vertical longitudinal sectional view of a smoothing plane equipped with my improvements.

Fig. 2 represents a top plan view of the plane, and

Fig. 3 represents a sectional view taken on line 3—3 of Fig. 1.

In the drawings, I have shown my improvement as applied to a construction or type of smoothing plane in common and general use, and it will not be necessary for me to specifically describe the construction of such plane.

My invention is of extremely simple construction and operates in conjunction with the transverse knife throat or passage A, and the knife or cutter B, and consists of the

milled roller C, mounted to permit an accommodating movement upon the shaft or rod D, such roller being held in proper relation to the knife by the pair of spring arms E, and in conjunction with said milled roller, I employ the comb-shaped guard F, carried upon the roller G, one of whose bearings H is mounted in the plane in stationary position, while its other bearing H', is mounted in an open bearing J of the plane, being retained therein by the spring retaining arm K, all as clearly shown in the drawing.

The operation of my invention will be readily understood by all persons skilled in such matters, and it will be apparent that the milled roller is disposed in such relation to the knife or blade B, as to cause the shavings made by the knife to be carried by the rotating action of said roller upward, then against the guard and discharged away from the plane, absolutely preventing any clogging or choking of the passage as is so common in planes in general use.

In view of the fact that my improvements are capable of application at a very small cost to smoothing planes at the time of manufacture or to planes in general use, and that such improvements will prevent choking or clogging of the knife passage and thus save considerable time and annoyance, it is evident that such improvements will commend the plane as useful, practical and highly efficient.

I claim:

1. In a smoothing plane and in combination with the knife and knife passage thereof, a roller yieldingly mounted in said passage to guide the shavings therethrough, and a guard disposed in proper relation to said yielding roller.

2. In a smoothing plane and in combination with the knife and knife passage thereof, a rotating member yieldingly mounted in said passage to guide the shavings therethrough, and a comb-shaped guard disposed in proper relation to said yielding member.

In testimony whereof I hereunto affix my signature.

HARRY W. HARGIS.
